DIRECT METHOD OF MAKING NEGATIVES
FOR USE IN GRAPHIC ARTSCaldwell A. Beattie, Gordon L. Glassford, and
William F. Dick, Pontiac, Mich., assignors to
A. B. Dick Company, a corporation of Illinois

Application September 14, 1937, Serial No. 163,848

11 Claims. (Cl. 41—46)

This invention relates to a direct method of making negatives for use in the graphic arts, and has for one of its objects the production of a process whereby complete opaqueness of the negative 5 may be obtained through a process of dyeing.

A further object of this invention is the provision of a process whereby a true image may be successfully converted from a stencil to a negative through a process of dyeing.

Another object of this invention is the provision of a process whereby practically all known kinds of shading may be transferred directly to a negative.

Another object of this invention is the provision of a method whereby a sharp, clear and exact reproduction may be produced in the nature of a negative from which a plate may be made, and a maximum number of copies may be run off from the printing plate.

Still another object of this invention is the ability to produce a negative directly without the aid of any photographic process.

Other objects and advantages of this invention will appear throughout the following specification and claims.

In the drawing:

Figure 1 is a perspective view illustrating the manner of tracing the image upon the transparent sheet constituting the first step of the 20 method;

Figure 2 is a perspective view of the transparent sheet showing the same being coated with dye or pigment of a suitable nature, this constituting the second step of the process;

Figure 3 is a transverse sectional view through the sheet showing the coating or dye upon one or both faces of the transparent sheet;

Figure 4 is an edge elevation of the negative illustrating one method of drying or removing moisture from the negative after dyeing; and

Figure 5 is an enlarged fragmentary plan view showing the type of impression made upon a sheet in the nature of a line and illustrating the general appearance of the line or impression made upon the sheet which is characteristic of the particular type of sheet preferably used, the impression being exaggerated.

In carrying out this invention a sheet of stencil paper is employed such as is commonly used in the art of stencil duplication, and which consists generally of a base sheet of open-texture, porous material, such as the well-known Japanese "Yoshino" paper, which base sheet is coated or impregnated with an ink-impervious material adapted to be removed in any desired areas. A typical image is designated by the numeral 11, and is traced upon the sheet 10 through the medium of a stylus or other impression medium, or typewritten words, as indicated by the numeral 12, may be impressed upon the sheet. Handwritten

ing, or other transposition methods may be employed without departing from the spirit of the invention. It should be understood that the particular type of stencil or transparent sheet which is used to provide a negative, will be stencilized; that is, converted into a stencil by displacement or removal of the coating by pressure, heat, solution or in any convenient manner, as through the use of a stylus or other transposition method, as is well-known to the art. It should be further understood that any suitable type of shading indicated by the numeral 13, may be employed, which is common in the art by using different types of styli, and suitable borders may also be used by employing different types of plates. Impressions may also be made by handwriting when desired, and it is not intended to limit this invention to any particular type of transposition.

After the stencil or transparent sheet 10 has been prepared with a suitable text, image, or the like, this transparent sheet or medium 10 is then preferably dyed with a black dye or any suitable dye color, the dye completely coating both surfaces, or one surface, of the sheet 10, the sheet being indicated by the numeral 14 and the wax, 25 cellulose, or other impervious coating by the numeral 15. The coating of dye indicated by the numerals 16 and 17 on the upper and lower faces respectively will adhere to the body of transparent medium but because of the stencilized 30 transposition such as the lines of the image, its shading, typewritten, or handwritten matter, will constitute perforated lines 18, preventing the adherence of the dye to the lines and presenting a 35 clear, sharp picture or reproduction in the nature of a negative.

In carrying out the method of dyeing, the dye may be spread upon the sheet 10 by means of a brush 20, as illustrated in Figure 3, or by means of a swab. If desired, the sheet may be soaked 40 or immersed in the dye. After the dyeing process has been completed, the excess dye is removed from the sheet by squeegeeing or blotting with a lintless paper, such for instance as a newspaper, or other suitable type of paper, in a manner as 45 shown in Figure 4. Any suitable means may be employed for removing the excess dye, in this way providing a uniform opaque background.

By following this method, a direct negative is produced, this negative may then be used in the 50 graphic arts in the same manner as other negatives are used, the negative having the ability to pass light through the image only as needed.

In carrying out the process, it has been found that practically no shrinking of the sheet occurs 55 and any such shrinking would be infinitesimally small. An image of absolute fidelity so far as reproduction by original drawing or impression is concerned, is provided by this process, and in fact 60 an exact copy is provided because of the fact that

no intermediary is used. Furthermore, a blackness and opaqueness not as yet ever attained in known commercial process of making negatives is provided by this method.

- 5 As a modified method in producing negatives for use in the graphic arts or for any stencil making process, we may first color the stencil or transparent sheet with an opaque color before the image is impressed thereon by applying a 10 dye or opaque pigment of suitable color to the transparent sheet as previously described. The image may then be impressed in the same manner 15 in any conventional manner without departing from the spirit of the invention.
- 16 It is further desired to cover the negative as used in any way even though it may be used to make photographic or water soluble stencils, and it should be understood that a wax, cellulose or 20 water soluble base transparent paper may be used.

In experimenting with this method above described, it has been found that not only the opaqueness required for the purpose intended is attained by the process or dyeing described above, 25 but that the additional step usually required known as opaquing the negative is entirely eliminated, and through this method a type of negative greatly superior to known negatives for producing printing plates is provided. It has been found 30 further that by using plates produced from the negative made by the method above described, that many thousand copies may be made from the plate as compared with the usual run of six to nine hundred copies by the direct plate method in 35 use at this time. Furthermore, every known kind of shading may be transferred directly to the negative with the possible exception of solid black in large areas, which latter would be difficult because of the frailness of the sheet. The image may 40 be transferred quite rapidly, and in about the same time that an ordinary pencil drawing might be made. As a result of careful research it is believed that the above method is the best method by which a true image may be successfully transferred 45 from a stencil except by photography, and that by following this method, a plate may be produced which may print a clearly defined sharp-lined image which is not possible through the use of stencil duplicated copies which must usually be 50 printed with a thin and oily ink, and upon paper having a high blotting quality. This method provides a very inexpensive method of producing a negative which may be used for producing plates and the like, for use in printing such for instance 55 as by means of an offset press, but it should also be understood that the negative may be used for blue-printing, ozalid printing, photographic printing, bromide printing, or for any stencil making process, and in fact in any place where a 60 negative is desired for use in the graphic arts.

It should be understood that certain detail changes may be made in the method described without departing from the spirit of the invention so long as these changes fall within the scope of 65 the appended claims.

Having described the invention, what we claim as new is:

1. A direct method of making a negative which 70 consists in first imprinting subject matter upon a sheet coated with a pressure displaceable film, by any well known transposition method, whereby the subject matter is perforated through the sheet, then dyeing the sheet to provide an opaque background for the imprinted subject matter, and

then drying the sheet by squeegeeing, blotting and the like with lintless paper, whereby a non-shrinking direct negative may be produced for use in the graphic arts.

2. A method of making a direct non-shrinking negative for use in the graphic arts which consists in first tracing an image by means of a stylus and the like upon a sheet of transparent paper coated with a displaceable film, then dyeing the sheet black with black dye by soaking, immersing, 10 brushing, swabbing, and the like, and then removing excess dye from the sheet.

3. A method of making a non-shrinking negative for use in graphic arts which consists in the steps of dyeing opaque a transparent stencil sheet 15 and in stenciling an image upon the sheet.

4. A method of making a direct non-shrinking opaque negative, for use in the graphic arts or any stencil making process, which consists in first, tracing an image by means of a stylus and the like 20 upon a stencil sheet, then dyeing the sheet with black dye or any other color dye, by soaking, immersing, brushing, swabbing and the like, thus providing an opaque background for the image placed upon the sheet, and then removing excess 25 dye from the sheet, whereby a non-shrinking direct negative is produced, without the aid of any photographic process.

5. A direct method of making a non-shrinking opaque negative, which consists in first, dyeing a 30 sheet of type or stylus impressible stencil paper, of the character described, with a black dye or any other color dye to provide an opaque sheet, then drying the sheet by squeegeeing, blotting and the like with lintless paper, and then imprinting the subject matter upon the sheet by any well known transposition method, whereby subject matter is 35 perforated through the dye sheet.

6. The method of making a negative of an image which consists in stenciling the desired 40 image on a stencil sheet, and then dyeing said stencil sheet to render opaque all portions thereof other than the image.

7. The method of making a negative of an image which consists in forming said image on a 45 transparent sheet coated with a pressure displaceable film so as to displace the coating in areas corresponding to the image, then dyeing said sheet to render opaque the remaining coated areas.

8. The method of making a negative of an image which consists in stenciling the desired image on a type and stylus impressible stencil sheet and then coating the stencil sheet with opaque coloring matter, and then removing said 55 coloring matter from the stenciled portion of the sheet.

9. The method of making a negative of an image which consists in stenciling the desired image in the pressure displaceable coating of a 60 stencil sheet which is dyed to render it opaque.

10. A direct method of making an opaque negative of a desired image, which consists in first saturating a stencil sheet with opaque dye, and then stenciling the desired image on said stencil 65 sheet.

11. A negative of a desired image for use in the graphic arts comprising a stencil sheet saturated with opaque dye and stenciled in the areas of the image.
